UNITED STATES PATENT OFFICE.

JOHN W. ENRIGHT, OF NEW ORLEANS, LOUISIANA.

STATIONARY CHEMICAL-MIXING FIRE-EXTINGUISHER SYSTEM.

1,319,518.

Specification of Letters Patent.

Patented Oct. 21, 1919.

Application filed March 10, 1919. Serial No. 281,690.

To all whom it may concern:

Be it known that I, JOHN W. ENRIGHT, a citizen of the United States of America, residing at New Orleans, in the parish of Orleans and State of Louisiana, have invented certain new and useful Improvements in Stationary Chemical-Mixing Fire-Extinguisher Systems, of which the following is a specification.

10 This invention relates to improvements in stationary chemical mixing fire extinguisher systems.

The principal object of the invention is to provide means of extremely simple and 15 inexpensive structural nature which shall be certainly and automatically operative under fire emergency conditions promptly to effect the discharge of acid into the tank which contains the alkaline solution.

20 An embodiment of the invention is illustrated in the accompanying drawing wherein the figure is a sectional diagram.

The system includes a tank 1 for an alkaline solution from which leads a riser 2, 25 extending throughout the height of the building and forming an element of the distributing system, the latter including the usual leaders or laterals 3 which are provided with sprinkler heads or distributing 30 valves 4.

In the embodiment disclosed and preferred, the acid is contained in an invertible bottle 5 which is arranged within an upward extension 6 of the tank 1 and which is pivoted off center to a bracket 7, the bottle 5 normally resting in stable equilibrium against an adjacent wall of the extension 6.

The bottle 5 in the embodiment disclosed has at one side thereof an open receptacle 8 and the over-turning of said bottle is effected by filling the receptacle 8 with the liquid which over-balances the bottle and causes it to fall by gravity into the inverted position shown by dotted lines. In its normal 45 position, the bottle 5 may be closed by a stopper 9 which is connected by a chain 10 to the top of the extension 6 and, as the bottle is over-turned, the stopper is disengaged, as will be obvious.

50 The liquid which is discharged into the receptacle 8 is normally contained in a reservoir 11 having in its top a small opening 12 which prevents a vacuum influence in said reservoir as the liquid is vented therefrom. The reservoir 11 is connected at its lower end to a pipe 13 which projects into a

vessel 14 containing mercury 15. The vessel 14 is also connected to a pipe 16 which leads to the extension 6 and whose discharge end alines with the receptacle 8. In charging 60 the system, the mercury 15 is placed in the receptacle 14, after which air or gas under pressure is charged into the riser 2 so as to fill the laterals 3 and also the extension 6 and the space in the tank 1 above the alkaline solution. By virtue of this, a column 65 of mercury is forced up the pipe 13 for a suitable distance, after which the operating liquid, preferably of a non-freezing variety, is placed in the reservoir 11 and is held 70 therein by the column of mercury in the pipe 13.

When a sprinkler head or distributing valve 4 opens at the time of a fire, the air or gas under pressure will, of course, escape 75 and the fall of pressure thus occasioned will result in the lowering of the mercury column in the pipe 13 to a point where the liquid in the reservoir 11 will overcome the mercury and flow through the trap and by way of 80 the pipe 16 to the receptacle 8. When the requisite amount of liquid has entered said receptacle, the acid bottle will be overturned, as will be obvious.

What is claimed is:—

1. A stationary chemical mixing fire extinguisher system comprising a tank for an alkaline solution, an invertible acid bottle, a normally empty liquid receptacle associated with said acid bottle and operable when filled with a liquid to effect the inversion of the acid bottle and the discharge of the contents thereof into said tank, a reservoir normally containing said liquid, a pipe for conducting the liquid from said reservoir to said receptacle, a mercury trap interposed between said reservoir and said pipe, and a distributing system normally containing a fluid which acts on the mercury in said trap to maintain the trap operative. 100

2. A stationary chemical mixing fire extinguisher system comprising a tank for an alkaline solution, an invertible acid bottle provided with an open, normally empty, liquid receptacle at one side thereof, a reservoir normally containing liquid, a pipe for conducting the liquid from said reservoir to said receptacle, a mercury trap interposed between said reservoir and said pipe, and a distributing system normally containing a fluid which acts on the mercury in said trap to maintain the trap operative, the said 105

liquid when filling said receptacle causing the inversion of the acid bottle and the discharge of the acid into the tank.

3. A stationary chemical mixing fire extinguisher system comprising a tank for an alkaline solution, an invertible acid bottle, a normally empty liquid receptacle associated with said acid bottle and operable when filled with a liquid to effect the inversion of the acid bottle and the discharge of the contents thereof into said tank, a reservoir normally containing the said liquid, a distributing system normally containing a fluid, a pipe to conduct the liquid from said reservoir to said receptacle and means under the control of said fluid for normally maintaining the liquid in said reservoir and preventing the flow of the liquid through said pipe, said means operating when the fluid in said distributing system is vented to permit the flow of said liquid through said pipe.

4. A stationary chemical mixing fire extinguisher system comprising a tank for an alkaline solution, an invertible acid bottle provided with an open, normally empty, liquid receptacle at one side thereof, a reservoir normally containing liquid, a pipe for conducting the liquid from said reservoir to said receptacle, a distributing system normally containing a fluid, and means under

the control of said fluid for normally maintaining the liquid in said reservoir and preventing the flow of the liquid through said pipe, said means operating when the fluid in said distributing system is vented to permit the flow of said liquid through said pipe, and said liquid, when filling said receptacle, causing the inversion of the acid bottle and the discharge of the acid into the tank. 35

5. A stationary chemical mixing fire extinguisher system comprising a tank for an alkaline solution, an invertible acid bottle, a normally empty liquid receptacle associated with said acid bottle and operable when filled with a liquid to effect the inversion of the acid bottle and the discharge of the contents thereof into said tank, a reservoir normally containing said liquid, a pipe for conducting the liquid from said reservoir to said receptacle, a mercury trap interposed between said reservoir and said pipe, and a dry-pipe distributing system normally containing air or gas which acts on the mercury in said trap to maintain the trap operative. 45 50 55

In testimony whereof I have hereunto set my hand in presence of two subscribing witnesses.
